CLAIM

The ornamental design for a microphone unit, as shown and described.

DESCRIPTION

FIG. 1 is a perspective view of a microphone unit, showing our new design, wherein a triangular light pipe for a touch sensitive mute is visible under a reflective top surface of the unit and is shown as being unilluminated;

FIG. 2 is another perspective view thereof;

FIG. 3 is a top plan view thereof;

FIG. 4 is a bottom plan view thereof;

FIG. 5 is a front elevational view of thereof;

FIG. 6 is a rear elevational view thereof;

FIG. 7 is a left side elevational view thereof;

FIG. 8 is a right side elevational view thereof;

FIG. 9 is another perspective view thereof, wherein the triangular light pipe for the touch sensitive mute is shown as being illuminated; and,

FIG. 10 is another top plan view thereof, wherein the triangular light pipe for the touch sensitive mute is shown as being illuminated.

The broken lines depicted in FIGS. 1-10 are for illustrating unclaimed portions and boundaries of the microphone unit and form no part of the claimed design.
